COMBINATION LOCK

Eric Maclean Young, Melbourne, Victoria, Australia, assignor to Cypher Lock Company Limited, Melbourne, Victoria, Australia

Application February 7, 1946, Serial No. 646,092
In Australia July 11, 1945

20 Claims. (Cl. 70—145)

1

This invention relates to combination locks of the type having a multiple number of coded discs adjustable to a predetermined setting determined by the selected code word or combination, to release a latch, bolt or locking mechanism associated with a closure member, door or the like.

The principal objective of this invention is to provide an improved combination lock of the type specified suitable for mass production, and readily adaptable for the locking of various closure members, but particularly useful for the locking of doors.

A further object of the invention is to provide such a lock of simple and economical construction in which the selected code or combination may be conveniently varied, and in normal use cannot be readily detected by unauthorized use or in an attempt to pick the lock.

A further object is to provide such a combination lock which is self-contained to eliminate the use of separate latching and locking devices and incidentally permit the opening of a door from within the room without having to employ the combination or coded release of the lock.

With the above stated objects in view, there is provided according to this invention, a casing, a multiple number of spring influenced coded discs mounted for rotation and axial movement in unison within the casing, a releasable locking means to co-operate with said discs, means operable from without the casing to rotate said discs, and relatively fixed means in said casing to coact with said discs in response to a reciprocal rotation of the latter, to axially move said discs against the influence of the spring into operative engagement with the releasable locking means.

In operation the discs are turned in a constantly reciprocal rotation i. e. the rotation is constantly changed from a clockwise to anti-clockwise turning in accordance with a pre-selected code or combination of words or figures, whereby the relatively fixed means first registers in sequence with each disc according to the code setting, in one direction of rotation, and upon the reverse direction of rotation coacts with the disc to axially advance the latter a distance equivalent to the space between the discs, which latter being in bank formation are axially advanced towards and ultimately engage with the locking means.

Other objects and features of the invention will be readily apparent from the accompanying drawings.

The accompanying drawings depict a practical arrangement of the combination lock according to this invention.

2

In these drawings:

Fig. 1 is a central section of the combination lock in the assembled and locked position in a door or the like.

Fig. 2 is a central section of the lock illustrating the bank of discs in the operative position to co-operate with the releasable latch member of the lock to open the door.

Fig. 3 is an external end elevation of the lock.

Fig. 4 is an interior end elevation of the lock.

Fig. 5 is a diagrammatic view in elevation of the bank of coded discs.

Figs. 6, 7 and 8 are perspective views of certain discs included in the bank of discs.

Fig. 9 is a detail sectional view taken on line 9—9 of Fig. 2, illustrating the means co-active with the bank of discs and latch member to actuate the latter and open the door.

Fig. 10 is a detail view of the means for holding the drum in position to actuate the latch member.

Fig. 11 is a section taken on line 11—11 of Fig. 2.

Fig. 12 is a section taken on line 12—12 of Fig. 2.

Fig. 13 is a section taken on line 13—13 of Fig. 2.

Referring to Figs. 1 and 2 of the accompanying drawings the casing 5 of the lock is cylindrical and housed in a correspondingly shaped aperture 6 in the panel of the door 7 adjacent the outer side of the latter. The end wall 8 of the casing 5 is formed with a central aperture 9 in which is journalled the stem 10 of a bearing 11 through which the squared end of the main spindle 12 extends and is exteriorly of the casing 5, fitted with the main control knob 13. Interposed between the inner end of the control knob 13 and outer surface of the end wall 8 of the casing, is a rotatable plate 14 which is disposed on the spindle 12 and located in the central opening 15a of a fixed dial plate 15 attached to the outer side of the door 7, said plate being of equivalent diameter to the cylindrical casing 5. The dial plate 15 is marked around the periphery of opening with radially arranged groups of figures and letters from which a combination of either letters or figures may be selected as the code for opening the lock.

An indicator or pointer 16 on the rotatable plate 14 is arranged to traverse the indicia on the dial plate 15 upon the turning of the knob.

Within the cylindrical casing 5, a drum 18 is mounted for rotatable and axial movement upon the spindle 12, the end wall 19 of the drum nor-

mally disposed in contact with the bearing 11 upon said spindle 12. The other end 20 of the drum 18 is of reduced diameter and threaded into a flanged disc 21 secured to the spindle 12 by the diametrical pin 22 extending through the flanged disc, threaded end of the drum 18, spindle 12 and inner axially disposed rod 23 located in said spindle 12. The spindle 12 in advance of the diametrical pin 22 (shown in the normal position in Fig. 1) is longitudinally slotted as at 24 to permit the movement of the pin along said spindle upon the axial movement of the drum 18 thereon; the drum being pinned to the spindle 12 the turning of the latter by the use of the control knob 13 effects a corresponding rotation or turning of the drum 18.

The outer end of the spindle 12 is journalled in the side wall 26 of the housing 27 containing the latch indicated generally at 28, said housing being attached to the flange 29 of the cylindrical casing 5 and to the door. A spring 30 is disposed upon the spindle 12 between the wall 26 of the latch housing 27 and outer threaded end of the drum 18, whereby axial movement of the latter upon said spindle in the direction of wall 26, is effected against the resistance of the spring 30.

The internal axial rod 23 within the spindle 12 projects beyond the latter, through the latch housing 27 and exteriorly of said housing is fitted with a control knob 31 for the purpose herein-after described.

Upon the drum 18 there is mounted a bank of coded discs indicated generally at 33 in Figs. 1 and 2, the bank in the arrangement illustrated comprising 8 discs between each of which latter is interposed a spacing washer 34 or spring washer of reduced diameter relatively to said discs.

Referring to Figs. 5 to 8 it will be noted that the discs 33 comprise flat circular plates composed of spring steel suitably tempered and of the required gauge.

The disc plates 33 are centrally apertured as at 36 to provide a machine fit upon the drum, which latter is provided with a number of peripheral slots 37 (Fig. 11) equivalent in number and spaced according to the spacing of the discs.

Within the central aperture 36 of each disc 33 is a lug 38 corresponding in shape to the shape of the slots 37, to engage with one of the latter so as to retain the discs in assembly upon the drum.

With the exception of the innermost and outermost discs 33a—33b respectively, all the discs 33 are formed with peripheral right angular openings or slots 39 defining angular vanes 40 disposed at an inclination to the periphery of the discs. On each disc 33 a number of idle vanes 40 are directed to one side of the discs while a pair of diametrically opposite vanes 40a are directed to the other or opposite side of the disc, said vanes 40a forming cam surfaces adjacent to the openings or slots 39a in said discs. The outermost disc 33b is provided only with the pair of diametrically opposite vanes 40a forming cam surfaces on one side thereof, and the innermost disc 33a is devoid of vanes but is provided on the inner face 33c (Fig. 5) with a number of depressed concentric dimples 42 and operates as a trap disc as hereinafter described.

Within the casing 5 in diametrically opposite relation are a pair of cam abutments 43—44 comprising cylindrical pin like extensions of screws 45 threaded into the wall of the casing 5. The cam abutments 43—44 are normally disposed between the innermost pair of discs 33a—33 as

viewed in Fig. 1, and in alignment with aligning peripheral slots 47 in the discs, as illustrated in Fig. 11.

The object of the cam abutments 43—44 is to co-operate with the bank of discs 33 to advance the same from the normal locked position (Fig. 1) against the compression spring 30 to the unlocking position (Fig. 2).

The bearing 11 rotatable with the spindle 12 and discs 33, has attached thereto one end of a spiral spring 48 the other end of which latter is anchored to the wall 8 of the casing 5. A pin 50 projecting radially from a bearing 11 under the influence of spring 48 normally engages with one of a pair of diametrically opposed stops 51—52 on the wall 8 of the casing to maintain alignment of the peripheral slots 47 in the discs 33 with the cam abutments 43—44 in the normal position. Stops 51—52 also limit the extent of partial rotation or angular movement of the bank of discs 33 and the spring operates to return said discs to the normal position upon completion of an unlocking movement, with the slots 47 therein aligning with the cam abutments 43—44. The flanged disc 21 threaded to the drum 18 carries on the outer face adjacent to the periphery thereof a roller 54 adapted to engage in the unlocking position of the bank of discs 33 (Fig. 2) with a plate 55 upon the inner end of the spring influenced latch bolt 56.

To set up the discs 33 upon the drum to accord with a coded word or group of figures selected from the dial plate 15, the code word for the opening of the lock is first selected, in this instance "Sesame." The discs 33 working from the one adjacent to the innermost one 33a are then mounted upon the drum by inserting the lug 38 in its slot 37 in the drum 18, the slot 37 being so disposed that upon the control knob 13 being turned to register the letter S with the indicator 16, the peripheral openings 39a in said disc defining the diametrically opposite vanes 40a will lie practically opposite to or behind the cam abutments a distance not greater than one spacing so that upon reverse turning of control knob 13 the vane 40a engages with the cam abutments 43—44 to pass through the peripheral openings 39a.

Indexing of the control knob a distance greater than one spacing would result in the vane 40 engaging with the cam abutments 43—44 to pass through the opening 39 which would cause an axial movement in the wrong direction (not against the compression of spring 30). The discs are successively mounted upon the drum 18, whereby the registration of the indicator 16 with the particular letter in the code word or combination of letters or figures, by turning the control knob 13, will in turn bring the cam abutments 43—44, opposite to the respective peripheral openings 39a in the discs defining the pairs of diametrically opposite vanes 40a; this set up being clearly illustrated in the diagrammatic elevation in Fig. 5, wherein the above described position of one cam abutment 43—44 in relation to an opening 39a in respect to each disc, is illustrated.

In operation the user would initially dial "S" by turning the control knob 13, locates the cam abutments 43—44 practically opposite each peripheral disc opening 39a in the first disc adjacent the innermost disc 33a, as viewed in Fig. 5; upon a reverse turning of said knob, to dial the letter "E," cam abutments 43—44 engage the 75 outwardly projecting and inclined vanes 40a on

said disc, which varies acting as a cam, as said abutments in effect pass through said openings 39a, cause an axial movement of the particular disc as the discs are partially rotated. The discs being in bank formation are axially advanced on the spindle 12 against the compression of spring 30 a distance equivalent to the space between said discs.

Accordingly as the control knob 13 is turned in a uniformly reciprocal and partial rotation, or in constantly reverse directions, to dial the remaining letters "S," "A," "M," "E," the cam abutments 43-44 in each instance engage the diametrically opposite and camming vanes 40a on each disc to cause the latter in each instance to axially move the distance stated, until the roller 54 upon the flanged disc 21 of the drum 18, engages the end plate 55 on the latch bolt 56.

As the camming vanes 40a and idle vanes 40 project into the space between each pair of discs 33, the cam abutments 43-44 having a wiping engagement with all the vanes as the discs are partially rotated, so that in the absence of the code word or combination, it is practically impossible to pick the particular vane which constitutes the camming vane 40a.

Having regard to the number of idle vanes 40 and discs 33, and the time factor the difficulty of picking the lock or combination to open the lock will be appreciated.

In view of the wiping contact of the cam abutments 43-44 with the vanes 40, 40a, the discs are either manufactured from spring steel to provide the requisite resiliency on the vanes 40, 40a to yield under the wiping contact of the cam abutments 43-44. Alternatively the discs may be composed of other metal and spring washers utilized as the spacing washers 34.

With the roller 54 in engagement with the inner plate 55 on the latch bolt 56, a partial anti-clockwise rotation of the discs 33 and spindle 11, causes the latch bolt to retract against the compression of its spring to permit the door to be opened.

Upon the control knob 13 being turned and released, the spindle is reversely rotated by the spring 48 to align the slots 47 in said discs with cam abutments 43-44 and the spring 30 then axially moves and returns the bank of discs freely past said abutments along the spindle to the normal position illustrated in Fig. 1.

To open the door from inside the room without having to resort to the use of the combination lock, the inner knob 31 is merely axially withdrawn with the inner rod 23 to similarly move the bank of discs 33 to the unlocking position illustrated in Fig. 2. This axial movement of the discs 33 is permitted by the discs moving past the cam abutments 43 which register with the slots 47 in the periphery of the discs 33. The roller 54 on flanged disc 21 then engages with the collar 55 to effect the retraction of the latch bolt 56 upon the turning of the knob 31. To lock the bank of discs 33 from within the room against coded adjustment by the operation of the external central knob 13 to unlock the door, as illustrated in Fig. 13 the spindle 12 has formed therein a radial slot 60 normally disposed in alignment with the stem 61 of a spring pressed plunger 62 projecting into the latch housing 27. Said plunger 62 carries a knurled head 63 outside the latch housing 27, the boss of the head having a pin 64 parallel to the plunger 62 and normally engaging a raised seating 65 on the housing. A slot 66 is formed

in the seating at the other side of the plunger and so disposed that when the latter is turned, the pin entering the slot 66 permits the plunger to axially move to bring its stem 61 into engagement with the slot 60 in the spindle 12. With the plunger 62 engaging the spindle 12 the latter is prevented from turning, whereby the main control knob 13 and resultantly the bank of discs 33 are restrained against movement.

As illustrated in Fig. 10, the latch 28 may be maintained in the retracted position illustrated in Fig. 2 by the use of the pin 22 in the internal rod 23 which is slidable in the elongated slots 24 in the spindle 12, said slots having arcuate extensions 79 so disposed that when the rod 23 is in the fully extended position and turned relatively to the spindle 12, the pin 22 engages the arcuate extensions of the slots 24 to thereby prevent retraction of the rod 23 and knob 31 under influence of the spring 30, and incidentally the return of the latch 28 to the normal position.

Although the lock has been described as applied to door, it may with suitable constructional variation, apart from the disc and cam assembly, be utilized with petrol drums or tank caps and other closure members for the locking of the latter.

I claim:

1. A combination lock comprising a casing, a bank of spring influenced coded discs mounted for rotation and axial movement in unison within said casing, releasable locking means to co-operate with said bank of discs, which latter are formed with cam surfaces, and relatively fixed means in said casing co-active with said cam surfaces in response to reciprocal rotation of said discs to axially move the discs against the influence of the spring into operative engagement with said releasable locking means.
2. A combination lock comprising a casing, a bank of spring influenced coded discs mounted for rotation and axial movement in unison within said casing, releasable locking means to co-operate with said bank of discs, a number of adjacent discs in said bank each peripherally slotted with cam surfaces projecting from the slots, and relatively fixed means in said casing co-active with said cam surfaces in response to reciprocal rotation of said discs to axially move the discs against the influence of the spring into operative engagement with said releasable locking means.
3. A combination lock comprising a casing, a bank of coded discs mounted for rotation and axial movement in unison within said casing, a spring arranged to resist the axial movement of said discs, a releasable locking means to co-operate with said discs, a number of adjacent discs in said bank each peripherally slotted with inclined vanes projecting from the slots each side of said discs, the vanes on one and the same side of each disc forming cam surfaces, and relatively fixed means in said casing coactive with said cam surfaces in response to reciprocal rotation of said discs to axially move the discs into operative engagement with said releasable locking means against the resistance of the spring.
4. A combination lock comprising a casing, a multiple number of spring influenced coded discs mounted for rotation and axial movement in unison within said casing, a releasable locking means to co-operate with said discs, means operable from without the casing to rotate said discs, and relatively fixed means in said casing to coact with said discs in response to a reciprocal rotation of

the latter to axially move said discs against the resistance of the spring into operative engagement with the releasable locking means.

5. A combination lock comprising a casing, a rotatable spindle journalled in said casing, a spring influenced bank of coded discs mounted for rotation and axial movement in unison upon said spindle, a releasable locking member to co-operate with said discs, a number of adjacent discs in said bank each peripherally slotted with inclined vanes projecting from the slots each side of said discs, the vanes on one and the same side of each disc forming cam surfaces, and relatively fixed means in the casing coactive with the said cam surfaces in response to a reciprocal turning of the spindle to axially move the bank of discs against the resistance of the spring into operative engagement with said locking member.

6. A combination lock comprising a casing, a rotatable spindle journalled in said casing, a bank of discs mounted for rotation and axial movement in unison upon said spindle, a releasable locking member to co-operate with the bank of discs, a spring arranged to resist the axial movement of said discs towards said locking member, a number of adjacent discs in said bank each peripherally slotted with inclined vanes projecting from the slots each side of said discs, the vanes on one and the same side of each disc forming cam surfaces, and relatively fixed means in said casing to successively co-act with each cam surface in response to a reciprocal turning of said spindle so as to axially move the discs into operative engagement with said locking member against the resistance of the spring.

7. A combination lock comprising a casing, a spindle journalled in said casing, means exteriorly of the casing to rotate the spindle, a bank of coded discs mounted upon said spindle within the casing for rotation with an axial movement in unison upon said spindle, a releasable locking member disposed in spaced relation to said discs to co-operate with the latter, a spring disposed on said spindle to resist the axial movement of said discs towards the locking member, a number of adjacent discs in said bank each peripherally slotted with inclined vanes projecting from the slots each side of said discs, the vanes on one and the same side of each disc forming cam surfaces, and a fixed cam abutment in said casing to successively register with the slots adjacent the cam surfaces and co-act with said cam surfaces responsive to a reciprocal turning of said spindle, whereby the bank of discs is axially moved against the resistance of the spring into operative engagement with said locking member.

8. A combination lock comprising a casing, a bank of spring influenced coded discs mounted for rotation and axial movement within said casing, means operable from without the casing to rotate said discs, a releasable locking member to co-operate with and actuatable by said discs, a number of adjacent discs in said bank each peripherally slotted with inclined vanes projecting from the slots each side of said discs, the vanes on one and the same side of each disc forming cam surfaces, and a fixed cam abutment in said casing located to successively register with the slots in said discs and co-act with said cam surfaces responsive to a reciprocal turning of said means operable from without the casing, whereby the discs are axially moved into operative engagement with the releasable locking member.

against the resistance of the spring influencing said discs.

9. A combination lock comprising a casing, a spindle journalled in and turnable from without said casing, a bank of spring influenced coded discs mounted upon said spindle for rotation and axial movement in unison, a spring pressed latch member spaced from said discs, and arranged normal to the axis of said spindle, a number of adjacent discs in said bank each peripherally slotted with inclined vanes projecting from the slots each side of said discs, the vanes on one and the same side of each disc forming cam surfaces, a fixed cam abutment in said casing to successively register with the slots adjacent to the cam surfaces and coact with said cam surfaces, responsive to a reciprocal turning of said spindle to thereby axially move the discs towards latch member, and means connected to said discs to engage in the advanced position of the latter with the latch member.

10. A combination lock comprising a casing, a spindle journalled in said casing, means exteriorly of the casing for turning said spindle, a latch housing attached to said casing, a spring pressed latch member located in said housing and arranged normal to the axis of said spindle, a bank of coded discs mounted for rotation and axial movement in unison upon said spindle, a spring disposed on said spindle to resist the bodily axial movement of said discs towards the latch member, a number of adjacent discs in said bank each peripherally slotted with inclined vanes projecting from the slots each side of said discs, the vanes on one and the same side of each disc forming cam surfaces, a fixed cam abutment in the casing to successively register with each slot adjacent to the cam surfaces and co-act with said cam surfaces responsive to a reciprocal turning of the spindle, to axially move said discs against the resistance of the spring towards the latch member, and means movable in unison with said discs to engage with and retract the latch member in response to a further rotational movement of the discs when in the advanced position.

11. In a combination lock according to claim 9, a spring arranged to resist the reciprocal turning or rotation of said discs upon the spindle.

12. In a combination lock according to claim 9, means operable from without the casing to engage said spindle at will, to restrain the turning of the latter.

13. A combination lock according to claim 6 and including a releasable locking member comprising a slidable spring pressed latch bolt arranged perpendicularly to the axis of the spindle, a plate carried on the inner end of the latch bolt, and a roller upon the adjacent end disc to engage with said plate in the advanced operative position of the discs so as to retract said bolt upon the turning of said discs.

14. In a combination lock, a spindle, a bank of spring influenced discs mounted for rotation and axial movement in unison upon said spindle, a number of adjacent discs each having a cam surface, and a fixed cam abutment coactive in sequence with said cam surfaces responsive to a reciprocal turning of the spindle to axially move discs against the resistance of the spring controlling the latter.

15. In a combination lock according to claim 14 and wherein each disc is provided with a peripheral slot, and a spring arranged to normally maintain the slots in alignment with each other and the cam abutment.

16. In a combination lock according to claim 4, means to lock said spindle against turning movements.

17. A combination lock comprising a rotary reciprocal and axially movable carriage, a bank of coded cam discs on the carriage, relatively fixed means co-active in sequence with the cam discs in response to reciprocal turning of the carriage in conformity with a pre-selected code to move the carriage from an inoperative position to an operative position, and locking means releasable by the carriage upon the latter attaining the operative position.

18. A combination lock comprising a rotary reciprocal and axially movable carriage, a multiple number of cam surfaces on the carriage, relatively fixed means co-active in sequence with the cam surfaces in response to reciprocal turning of the carriage in conformity with a pre-selected code to axially move the carriage from a normal position to an operative position, a lock releasing element on the carriage, locking means engaged by the lock releasing element as the carriage arrives at the operative position and being unlatched responsive to rotation of said carriage, and means for automatically returning the carriage to the normal position.

19. A combination lock comprising a rotary reciprocal and axially movable carriage, a multiple number of cam surfaces on the carriage, relatively fixed means co-active in sequence with the cam surfaces in response to reciprocal turning of the carriage in conformity with a preselected code to axially move the carriage from a normal position to an operative position, a lock releasing element on the carriage, locking means engaged by the lock releasing element as the carriage arrives at the operative position and being unlatched responsive to rotation of said carriage,

a return spring energized by axial movement of the carriage to the operative position, and a spring opposing rotation of the carriage and positioning said carriage for restoration to the normal position by the return spring.

20. A combination lock comprising a rotary reciprocal and axially movable carriage, a bank of discs on the carriage, cam surfaces on the discs, relatively fixed means co-active with the cam surfaces to axially advance the carriage from an inoperative position to an operative position, responsive to reciprocal turning of the carriage in conformity with a preselected code, slots formed in the discs adjacently to the cam surfaces and permitting said discs to pass the relatively fixed means in sequence during the reciprocal turning of the carriage, locking means engageable and releasable by the carriage upon the latter being axially moved to the operative position, aligned peripheral return slots in the discs, a return spring energized by axial movement of the carriage to the operative position, and a spring opposing rotation of the carriage and upon release of the locking means registering said return slots with said relatively fixed means for restoration of the carriage to the normal position by the return spring.
